(57) **CLAIM**

The ornamental design for a toddler slide set, as shown and described.

DESCRIPTION

FIG. 1 is a top, front, right side perspective view of a toddler slide set, showing my new design;

FIG. 2 is a bottom, rear, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of a portion indicated in FIG. 7.

The broken lines in the drawings show portions of the toddler slide set that form no part of the claimed design. The dash dot dash lines in FIGS. 7 and 9 are for the purpose of depicting the cut line of the enlarged view and form no part of the claim.
